CLAIM

The ornamental design for a display screen with animated graphical user interface, as shown and described.

DESCRIPTION

FIG. 1 is a front view of a first image of a display screen with animated graphical user interface showing the new design; FIG. 2 is a front view of a second image of FIG. 1; FIG. 3 is a front view of a third image of FIG. 1; and, FIG. 4 is a front view of a fourth image of FIG. 1.

The appearance of the image transitions between the images shown in FIGS. 1-4. The process or period in which an image transitions to another image forms no part of the claimed design.

The dot-dash broken lines illustrate a display screen and are the boundary of the claimed design. The remaining broken lines illustrate portions of the animated graphical user interface. None of the broken lines form part of the claimed design.
